(57) **CLAIM**

The ornamental design for a ceiling fan blade, as shown and described.

DESCRIPTION

FIG. 1 is a perspective view of a ceiling fan blade showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and

FIG. 7 is a bottom plan view thereof.

FIG. 8 shows one application of the present invention, wherein the blades are expanded; and,

FIG. 9 shows one application of the present invention, wherein the blades are closed.

The broken line showing of a ceiling fan is included for the purpose of illustrating environmental structure and forms no part of the claimed design.
